CONTAINER CLOSURE

Olaf I. Waring, Flushing, N. Y., assignor to Ferdinand Gutmann & Co., New York, N. Y., a corporation of New York

Application November 27, 1936, Serial No. 112,883
Renewed December 28, 1937

11 Claims. (Cl. 215—7)

The invention relates to container closures, and more particularly to a closure so constructed as to prevent the refilling or adulteration of the contents of a container without detection.

It is not an uncommon practice for unscrupulous merchandisers to refill containers with inferior stock, or to remove a part of the contents of a container and dilute the original product. Sometimes counterfeit labels and closures are used in the packaging of inferior merchandise. Such practices, in addition to reducing the volume of business of a legitimate producer by the palming off of inferior merchandise in containers bearing its labels and closures, adversely affect the reputation of the merchandise with the public because of such inferiority. Losses to legitimate producers from the above sources may be very great. Reduced sales and a reputation for a poor product are not the only sources of loss since advertising and sales cost, with a reduced demand, show further great losses when the demand thus created is supplied by inferior merchandise furnished by others.

With the above conditions in mind, a container closure is provided by the invention which embodies therein a disc having impressed thereon a safety design attesting the genuineness of the contents of the container, which design may embody safeguards against counterfeiting commonly found in bank notes, stamps and negotiable instruments of various kinds, and in addition thereto may be so moistened as to smudge the design to determine the genuineness or legality of the source of the merchandise and prevent reuse of the disc. Furthermore, the closure is so constructed that it cannot be removed from the container without so mutilating this protecting disc as to clearly indicate that the closure has been removed from the container.

The closure is of the re-seal type, and the sealing of the container is effected by means of a compressible friction liner or gasket acting directly against and frictionally engaging the top of the mouth of the container.

The fraud prevention feature resides in an identifying disc of rupturable material exposed through an opening in the top of the closure and positioned between this top and a non-resilient backing for the liner or gasket. A turning of the metal shell in relation to the liner or gasket and its backing and to said identifying rupturable disc, is relied upon to cause a mutilation of said disc which in itself is not utilized to form a liquid tight joint between the closure and the container. Consequently, the use of an adhesive

upon or about the top of the container mouth is unnecessary.

Prior to the present invention, the practice of interposing a disc of rupturable material between a sealing gasket in the shell and the neck of the bottle or other container has been extensively followed, this inner sealing disc having been cemented to the neck of the container to prevent access to the container without rupturing said disc.

With the packaging of many beverages, such as ardent liquors, the presence of an adhesive about the pouring lip at the mouth of the container may be objectionable, so that in producing the container of the invention, a construction has been employed which does not require the use of any adhesive upon or about the top of the container neck, the effectiveness of the seal being secured solely by the engagement of the liner or gasket within the metal shell and the neck of the bottle.

This liner or gasket is preferably of highly compressible friction material, and a backing plate is provided between it and the disc exposed through the open top of the container to permit the turning of the metal shell independently of the liner or gasket for the purpose of ensuring the rupturing of the disc before any turning movement is imparted to the liner or gasket.

The construction and arrangement of parts is such as to permit the rotation of the closure in its entirety to effect the sealing of the container by means of the liner or gasket before the means carried by the metal shell for rupturing the disc have been set to establish a relation of parts to cause a rupturing of the disc with a reverse rotation of the closure when removing it from a container.

The invention consists primarily in a container closure embodying therein a metal shell having a screw threaded skirt and an opening through the top thereof, a disc of rupturable material within said shell and exposed through said opening, a liner or gasket of compressible friction material within said shell, a plate having a recessed portion between said gasket and said disc, and a prong extending inwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use; and in such other

novel features of construction and combination of parts as are hereinafter set forth and described, and more particularly pointed out in the claims hereto appended.

5 Referring to the drawing,

Fig. 1 is a view of a fragmentary portion of the neck of a container with a portion of the closure broken away;

Fig. 2 is a plan view of Fig. 1;

10 Fig. 3 is a view of the rupturable disc after the removal of the closure from the container;

Fig. 4 is a plan view of the grooved plate interposed between the top of the sealing gasket and the disc of rupturable material;

15 Fig. 5 is a plan view of the closure prior to its application to a container; and

Fig. 6 is a section on the line 6—6 of Fig. 5.

Like numerals refer to like parts throughout the several views.

20 In the accompanying drawing, the invention is shown in connection with a container 10 of glass or other material having about the neck thereof exterior means such as screw threads 11 permitting the application to the container of a closure by a turning movement thereof.

The closure proper consists of a metal shell having a skirt 12 provided with means such as screw threads 13 co-operating with the co-operating exterior attaching means upon the neck of the container. This metal shell has an opening 14 through the top thereof affording an edge rim 15 for compressing a liner or gasket into the desired sealing contact with the top of the neck of the container 10.

35 Within the metal shell is a sealing liner or gasket 16 adapted to engage the top of the neck of the container, as shown in Fig. 1, and to be so compressed by the rim 15 as to form an effective sealing joint about the top of the neck of the container. This gasket must possess two characteristics. It must be sufficiently compressible to form a tight seal when applying the closure, and it must be such as to develop sufficient friction while engaged with the neck of a container to 45 permit a turning movement of the metal shell independently of the liner or gasket when removing the closure, until the compression on the gasket has been relieved. A soft vulcanized rubber liner or gasket has been found to give the desired mode of operation to the closure, and while a disc liner or gasket is shown in the drawings, it is obvious that the only portion thereof effective in forming the seal is the edge portion. While soft vulcanized rubber is above referred to, 50 it is obvious that cork, an admixture of cork or granular cork and rubber, or other materials possessing the above qualities may be used. Compressibility of the material and capability of developing friction while under compression are the 55 main requisites of the material to be used in this liner or gasket.

Upon the top of the liner or gasket 16 is a plate 17 having a rim portion 18 and a groove 19 within this rim portion and below the opening 65 14 in the metal shell. Continuity of the depressed portion or groove 19 of the plate 17 is not essential, although it facilitates the assembly of the plate in the closure structure when producing same. The raised central portion of the plate 17 is desirable but not essential, as will more fully appear hereinafter.

The edge nubs 20 are for the purpose of centering the plate 17 in relation to the metal shell with the development of a minimum of friction between 70 the edge of the plate and the skirt 12, but any

other means of affording friction reducing clearance about the edge of the plate, such as having an entire plate of slightly less diameter than the top of the shell, may be employed.

While the plate 17 may be of metal, it is obvious that other materials may be used.

When the closure is applied to a container, there will not only be friction developed between the liner or gasket 16 and the top of the bottle, but between said liner or gasket and said plate 17.

Between the plate 17 and the top of the metal shell so as to be exposed through the opening 14 in the top of said shell, is a disc 21 of fibrous or other suitable rupturable material having impressed thereon a safety design, indicated conventionally at 22, making the duplication or counterfeiting of such discs as difficult as possible.

In the use of the closure, the disc 21 must have little or no turning movement independently of the plate 17 and the liner or gasket 16, and while the pressure exerted by the edge rim 15 of the metal shell may cause said disc to cohere by friction to the plate 17 sufficiently to prevent independent movement of the disc, it may be found desirable to bind said disc to said plate by some suitable adhesive or cement.

The disc 21 is of a diameter to extend between the rim 18 of the plate 17 and the edge rim 15 of the screw cap shell and across and covering the groove or grooves 19 in said plate.

If desired, the safety design 22 impressed upon the disc 21 may contain water soluble coloring matter and a water insoluble pigment, so that the genuineness of this disc may be determined by wetting it to an extent to cause the water soluble 35 coloring matter to form a smudge without destroying the design itself which consists largely of water insoluble pigment. The raised central portion of the plate 17 affords a backing for this portion of the disc to facilitate the test above referred to without accidental rupturing of the disc.

It is essential, in a closure embodying the invention, that means be provided whereby when a closure is removed from a container, the material of the disc 21 shall be so torn or mutilated 45 as to assure detection in the event that a closure has been removed from a container. This mutilation of the disc also prevents a re-use of the closure. This characteristic of the closure is an important factor of safety in the merchandising 50 of the materials packaged by means of the container and the closure of the invention. It does not afford any safeguard so far as the dispensing of liquor from an opened container is concerned.

To ensure the above mode of operation, I provide the edge rim 15 of the metal shell with one or more inwardly and upwardly directed pointed cutting prongs 23. These prongs have a downwardly directed point, and before the application of the closure to a container, are positioned in 60 their entirety upwardly beyond the plane of the top of the metal shell so as not to engage and mutilate the disc 21 when applying the closure to a container by a turning movement. Preferably, the prongs 23 are arcuate in form, as shown more particularly in Figs. 5 and 6 of the drawing, so as to have a downwardly directed point positioned above the groove 19 in the plate 17. By thus positioning the prongs, they may, by the application 65 of pressure downwardly thereof by a plunger of a capping machine or in any other desired manner, be made to pierce the material of the disc 21 after the gasket 16 has been compressed to its maximum extent in forming the seal.

The operation of a closure embodying the invention is substantially as follows:—

When assembling the closure, the security disc 21, the top plate 17 and the sealing liner or gasket 16 are assembled in a metal shell in the relation shown in Fig. 1 of the drawing. If desired, the disc 21 may be glued or cemented to the disc 17 before or during the assembling of the parts in the manner above described. When the 10 parts of the closure have been thus assembled, the prong or prongs 23 will be positioned as shown in Fig. 6 of the drawing.

The closure may be applied to a container by means of an ordinary screw capping machine in the usual manner, thus engaging the gasket 16 with the top of the neck of a bottle and compressing the edge portion thereof between the bottle and the edge 18 of the plate 17 by means of the edge 15 of the metal shell.

20 When the closure has been firmly secured to the container, pressure is applied to the tops of the prongs 23, thus forcing them downwardly until they pierce the material of the disc 21.

When opening the container it is merely necessary for the user to impart a reverse turning movement to the closure. During the first portion of this movement, the metal shell will turn independently of the packing liner or gasket 16, the plate 17 and the rupturable disc 21, and the 30 prong or prongs 23 will move along the groove 19 and tear the material of the disc 21 in the manner indicated at 24 in Fig. 3.

The shell of the closure being of thin metal, the tears 24 will be jagged and irregular. The 35 tearing of the disc 21 will continue so long as the fraction between the disc 16, the top of the bottle and the plate 17 is sufficiently great to resist turning movement of these parts.

If it be attempted to raise the prongs 23 before 40 removing a closure from a container, these prongs will be so distorted or broken as to prevent their being again forced downwardly to pierce the disc 21. Furthermore, it would be extremely difficult to accurately position the prongs in relation to 45 previously formed openings in the disc 21 so as to avoid slight apparent mutilation of said disc, even if it were possible to again bend the prongs in a manner to make a clean, sharp opening through the material of the disc. Furthermore, 50 the material of the disc would ordinarily be mutilated when attempting to raise the prongs.

In actual experience it has been found that with a fairly heavy paper, the mutilations of the disc by each prong 23 will continue for a distance slightly less than 90° of movement of the metal shell, but with thinner, more readily rupturable material and with a lower pitch of the co-operating securing means 11 and 13, the entire central portion of the disc 21 may be cut from 60 the disc.

It is obvious that with the parts shown in Fig. 1 there are no projecting parts of the top of the metal shell which would injure the hands of the person removing the closure.

65 The mutilation of the disc will inform any purchaser that the closure has been removed from the container, so that it is impossible to refill, dilute or adulterate the contents of a container without destroying the salability thereof.

70 The use of the safety design 22 prevents the use in the closure of discs from unauthorized sources. By impressing a smudgable design 22 upon the disc 21, the purchaser of the merchandise in containers may, by wetting the portion of 75 the disc exposed through the opening 14, de-

termine the genuineness of the merchandise. Such smudging will not impair the salability of the container, but will assure a purchaser that the contents of a container have not been tampered with.

The prongs 23 must be of a length and so formed as to avoid binding engagement thereof with the grooves 19 of the plate 17, since a free movement of the metal shell in relation to said plate is essential to a successful operation of the 10 closure.

It has been demonstrated that with a closure constructed and operating as above described, the disc 21 will invariably be mutilated with the removal of the closure from a container.

A closure embodying the invention may be produced by machine equipment now commonly used in the production of re-seal caps of the general type to which the invention relates, at but slightly increased cost over the ordinary closure 20 of the type.

In the accompanying drawing, the various parts are shown upon an enlarged scale.

It is not my intention to limit the invention to the particular form and dimensions of the parts 25 entering into the container, nor to the particular material specified, there being a wide range of materials which will ensure the desired retardation of the movement of the packing liner or gasket, the top plate 17 and the disc 21 in 30 relation to the metal shell when removing the closure from the container.

The free turning of the shell during the application of the closure to a container after the development of sealing pressure is immaterial 35 to the invention, since such turning movement will occur prior to the piercing of the disc 21 by the prong or prongs 23.

Having described the invention, what I claim as new and desire to have protected by Letters 40 Patent, is:—

1. A container closure embodying therein a metal shell having a screw threaded skirt and an opening through the top thereof, a disc of rupturable material within said shell and exposed through said opening, a liner or gasket of compressible friction material within said shell, a plate having a recessed portion between said gasket and said disc, and a prong extending inwardly of the opening through the top of said shell and adapted, after the sealing of a container, to be forced downwardly to penetrate the portion of said disc across the recessed portion of said plate, whereby rotary movement of said shell to remove said closure will cause the 55 tearing of said disc to an extent to prevent its re-use.

2. A container closure embodying therein a metal shell having a screw threaded skirt and an opening through the top thereof, a disc of rupturable material within said shell and having impressed thereon a safety design exposed through said opening to prevent counterfeiting of said disc, a liner or gasket of compressible friction material within said shell, a plate having a recessed portion between said gasket and said disc, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.

3. A container closure embodying therein a metal shell having a screw threaded skirt and an opening through the top thereof, a disc of rupturable material within said shell and having impressed thereon in an ink containing water soluble coloring matter, a safety design exposed through said opening to prevent counterfeiting of said disc, a liner or gasket of compressible friction material within said shell, a plate having a recessed portion between said gasket and said disc, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.
4. A container closure embodying therein a metal shell having a screw threaded skirt and an opening through the top thereof, a disc of rupturable material within said shell and exposed through said opening, a liner or gasket of compressible friction material within said shell, a metal plate having a recessed portion between said gasket and said disc and a raised central portion forming a backing for said disc, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.
5. A container closure embodying therein a metal shell having a screw threaded skirt and an opening through the top thereof, a disc of rupturable material within said shell and having impressed thereon a safety design exposed through said opening to prevent counterfeiting of said disc, a liner or gasket of compressible friction material within said shell, a metal plate having a recessed portion between said gasket and said disc and a raised central portion forming a backing for said disc, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.
6. A container closure embodying therein a metal shell having a screw threaded skirt and an opening through the top thereof, a disc of rupturable material within said shell and having impressed thereon in an ink containing water soluble coloring matter, a safety design exposed through said opening to prevent counterfeiting of said disc, a liner or gasket of compressible friction material within said shell, a metal plate having a recessed portion between said gasket and said disc and a raised central portion forming a backing for said disc, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.
7. A container closure embodying therein a

metal shell having a screw threaded skirt and an opening through the top thereof, a disc of rupturable material within said shell and exposed through said opening, a liner or gasket of compressible friction material within said shell, a plate having a recessed portion between said gasket and said disc, and an arcuate prong extending inwardly and upwardly of the opening through the top of said shell and having a downwardly projected point, said prong being adapted, after the sealing of a container, to be forced downwardly to penetrate the portion of said disc across the recessed portion of said plate, whereby rotary movement of said shell to remove said closure will cause the tearing of said disc to an extent to prevent its re-use.

8. A container closure embodying therein a metal shell having a screw threaded skirt and an opening through the top thereof, a disc of rupturable material within said shell and exposed through said opening, a liner or gasket of compressible friction material within said shell, a plate having a recessed portion between said gasket and said disc, and a plurality of arcuate prongs at spaced intervals about the opening in the top of said shell, each prong extending inwardly and upwardly of the opening through the top of said shell and having a downwardly projected point, said prongs being adapted, after the sealing of a container, to be forced downwardly to penetrate the portion of said disc across the recessed portion of said plate, whereby rotary movement of said shell to remove said closure will cause the tearing of said disc to an extent to prevent its re-use.

9. A container closure embodying therein a metal shell having a screw threaded skirt and an opening through the top thereof, a disc of rupturable material within the said shell and exposed through said opening, a soft vulcanized rubber liner or gasket within said shell, a plate having a recessed portion between said gasket and said disc, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.

10. A container closure embodying therein a metal shell having a screw threaded skirt and an opening through the top thereof, a disc of rupturable material within said shell and exposed through said opening, a liner or gasket of compressible friction material within said shell, a plate having a recessed portion between said gasket and said disc and secured thereto by means of an adhesive, and a prong extending inwardly and upwardly of the opening through the top of said shell and adapted, after the sealing of a container, to be forced downwardly to penetrate the portion of said disc across the recessed portion of said plate, whereby rotary movement of said shell to remove said closure will cause the tearing of said disc to an extent to prevent its re-use.

11. A container closure embodying therein a shell having a skirt provided with attaching means permitting attachment of said shell to the neck of a container by turning movement of the shell, and an opening through the top thereof, a disc of rupturable material within said shell and exposed through said opening, a liner or gasket of compressible friction material within said

shell, grooved means surmounting said liner or gasket and engaging said disc, and a prong formed integrally with the material of said shell and extending inwardly and upwardly of the opening through the top of said shell and adapted, after the sealing of a container, to be forced

downwardly to penetrate the portion of said disc across the grooved portion of said grooved means, whereby rotary movement of said shell to remove said closure will cause the tearing of said disc to an extent to prevent its re-use.
